THOMAS H. GARY, OF BRISTOL, MARYLAND.

Letters Patent No. 86,979, dated February 16, 1869.

IMPROVEMENT IN DUMPING-WAGONS.

The Schedule referred to in these Letters Patent and making part of the same.

To all whom it may concern:

Be it known that I, THOMAS H. GARY, of Bristol, in the county of Anne Arundel, and State of Maryland, have invented a new and improved Dumping-Wagon and Car; and I do hereby declare that the following is a full, clear, and exact description of the construction and operation of the same, reference being had to the accompanying drawings, making a part of this specification, in which my invention is represented by a longitudinal vertical section.

This invention relates to that class of wagon-bodies and cars which can be tilted so as to dump the load in the rear; and

The improvement consists in a new apparatus by which the wagon or car can be operated more easily than heretofore.

In the drawings, the wheels, tongue, and axles are shown in red lines; the rest of the apparatus, showing the wagon-body in its horizontal position, ready to receive the load, is represented in buff; and the same apparatus, showing the wagon-body tilted down to dump the load, is represented in blue lines.

A represent the longitudinal side-pieces of the frame;

B, the bolster; and

C, a cross-beam, resting above the rear axle, the parts being so arranged that the side-pieces decline slightly toward their rear end, so that the wagon-body shall slide easily toward the rear, when necessary to dump the load.

Fixed to each of these two side-pieces is a stout board or longitudinal piece, D, extending back as far as the point d, and provided with a longitudinal slot, e, to receive and accommodate one of the rollers, hereinafter described.

Hinged at m, to the cross-beam C, is a tilting frame, E, of the same dimensions as the side-pieces D, except as to length.

This frame is provided with a slot, e, corresponding in dimensions to the slot e, for the purpose of accommodating the rear roller.

F G are the two rollers upon which the wagon or car-body H can be easily slid forward or back, as oc-

casion may require, said body resting upon these rollers, in the manner shown clearly in the drawing. As the body slides forward, these rollers run forward to the front ends of the slots, and as it slides back, they, in the same manner, run back to the rear end of the slots.

In order to keep the rollers in the proper position, projecting pins n n, acting against them, or a bent rod, N, encompassing them, may be employed, said pins or rod, or both, being attached to the sliding body H.

When the wagon-body is slid forward on the rollers, the corners of its frame at a a run under projecting flanges a' a', attached to the side-pieces D D, and thereby the body H is prevented from tilting until it is slid back again. It may be fastened in this position by any suitable means, so as to prevent its sliding back until the attendant desires to dump the load.

The ends of the rollers F G are provided with heads or collars, which prevent them from becoming detached from the apparatus, or from getting very much awry.

The operation of this improved apparatus is very simple, and is clearly shown in the drawing. By sliding the body H back so as to disengage the parts a a', it can be tilted, with the frame E upon the hinge m. The load having been dumped, the body is dropped to a horizontal position again, and slid forward till the end a runs under the flange a', which holds it in that position, as above described.

Having thus described my invention,

What I claim as new, and desire to secure by Letters Patent, is—

The combination of the body H, tilting frame E, hinged to the cross-beam at m, tongue and flange a a', and rollers F G, said parts being constructed and adapted to operate together, in the manner and for the purposes herein set forth.

To the above specification of my improvement, I have set my hand, this 12th day of January, 1869.

THOS. H. GARY.
